SOFA OR THE LIKE

Thomas Winrow, Naperville, Ill., assignor to Mohasco Industries, Inc., Amsterdam, N.Y.

Filed Dec. 28, 1971, Ser. No. 213,233

Term of patent 14 years

Int. Cl. D6—01

U.S. Cl. D6—63

FIG. 1 is a perspective view of a sofa or the like showing my new design;

FIG. 2 is an enlarged fragmentary perspective view of the right side of the sofa or the like shown in FIG. 1, looking in the direction of the arrow; and

FIG. 3 is a perspective view of a sofa or the like showing a second embodiment of my new design, which differs from the first embodiment in that it consists of just two back and seat cushions. The backs of the two embodiments are conventionally plain while the sides not shown are substantially identical to the sides shown.

I claim:

The ornamental design for a sofa or the like, as shown and described.
